UNITED STATES PATENT OFFICE.

JOHN H. COMER, OF LIBERTY HILL, TEXAS.

SILO.

1,343,809.

Specification of Letters Patent. Patented June 15, 1920.

Application filed October 21, 1918. Serial No. 258,992.

To all whom it may concern:

Be it known that I, JOHN H. COMER, a citizen of the United States, residing at Liberty Hill, in the county of Williamson and

5 State of Texas, have invented new and useful Improvements in Silos, of which the following is a specification.

This invention relates to a silo, and more particularly to a device of the type indicated intended to be constructed in sections, 10 to permit of shipment in a knock-down condition, and to permit of assembly at any desired point by means of inexperienced or unskilled workmen.

15 A further object is to provide a structure of the type indicated formed in a plurality of segments each constituting a segment of the completed structure, and each comprising an inner and outer layer of longitudinal 20 strips separated by insulating material, with certain novel means for connecting the segments when assembled.

25 A still further object is to provide a plurality of segments constructed as indicated and each provided with a portion at the edge thereof designed to overlap an adjacent segment, with means for temporarily securing the segments during construction, and certain novel means for permanently securing segments.

30 A still further object is to provide a structure formed as indicated and including annular members built up of segments formed of overlapping strips of material, these segments being secured together by tension means and serving to retain the longitudinal segments of the structures permanently in position to form the complete device.

With the foregoing and other objects in view, the invention consists in the novel construction, combination, and arrangement of elements hereinafter described and claimed.

In the drawings,

45 Fig. 1 is a view of the complete silo in elevation,

Fig. 2 is a transverse section on the line 2—2 of Fig. 1,

50 Fig. 3 is a detail view of a tension device,

Fig. 4 is a perspective view of a plurality of segments secured together,

55 Fig. 5 is a detail view, showing the built-up circumferential bands, in transverse section,

Fig. 6 is a transverse section on the line 6—6 of Fig. 1 and showing means for securing the door.

In carrying out my invention I provide a structure comprising a plurality of longitudinal segments, which will be termed sections in order to distinguish them from the portions or parts of the rings or hoops surrounding the structure and retaining the longitudinal sections in position.

65 The longitudinal sections referred to are designated at 10 and each comprises an inner layer of longitudinal strips 11, and an outer layer of longitudinal strips 12, these layers being separated by a sheet of insulating material, designated at 13. This insulating material may be of any suitable commercial type of roofing material. At one edge portion of each section 10 the outer 70 layer overlaps the inner layer, and at the opposite edge of each section the inner layer overlaps the outer layer, thus providing for the overlapping of adjacent segments or sections throughout the circumferential portion of the structure as completed.

75 In order to temporarily retain the longitudinal sections of the structures in position, during erection, I provide segmental hoop portions designated at 16, each segment having secured to the outer edge thereof 80 a metallic band 17. Ears 18 project laterally from the end of each segment, and the ears are provided with apertures 20, bolts passing through adjacent ears of adjacent segments, and serving to secure the 85 several segments of a complete ring or hoop in position for temporarily retaining the longitudinal sections of the structure, until permanent securing means are provided.

90 After the work has been completed to the point indicated, the permanent circumferential bands or hoops are applied, beginning at the bottom of the structure. The first temporary annular member or hoop is removed, and a permanent circumferential 100 band 25 is placed in position and suitably secured. This band is built up from a plurality of segmental portions. An inner band 26 of considerable width is applied to the longitudinal sections of the structure, and an additional band of less width is applied alongside of the band 26, the band of less width being designated 27. A band 28 105 is applied over the band 27 and extends partly over the adjacent band, thus breaking 110

the joint. Finally an additional narrow band is applied over the band 26, the various portions being secured by nailing, or in any other suitable manner.

5 After the permanent circumferential bands have been applied in the manner indicated, a tension device comprising a metallic band 30 is passed around the built up bands, the ends of the tension band being threaded 10 into engaging devices 31 and 32. All of the temporary circumferential members are replaced in a similar manner, and the main portion of the structure is complete. A top is shown at 35 and a ladder extends from 15 the bottom to the top, the ladder being designated at 36.

Certain of the longitudinal sections of the complete structure are provided with doorways at points on opposite sides of the 20 ladders, and arranged in the relative positions shown. The doors are designated 40 and are each formed of inner and outer layers of longitudinal strips, the inner layers being designated 42 and the outer layer 43. 25 These layers are separated by strips of insulating material, 44, as is the case of the longitudinal sections of the completed structure. The doors open from the inside, and the inner layer or portion 42 overlaps the 30 edges of the outer layers on all sides, and all of the edge portions of the inner and outer layers are covered with insulating material. The edge portions of the door-way are correspondingly formed, so that the

outer layers of longitudinal strips along the 35 lines of the edge of the door-way overlap the edge of the inner layers of longitudinal strips, this arrangement providing an effective joint practically air tight. Transverse metallic strips 48 aid in retaining the 40 strips of the outer portions of each door in position, and pivoted fastening devices 15 serve to secure the doors and prevent displacement from any accidental cause.

It is obvious that the relative sizes and 45 proportions of the various elements may be varied as may be desired, and other minor changes may be made within the scope of the appended claim.

Having thus described my invention I 50 claim:—

In a device of the class described, a plurality of longitudinally extending sections forming segments of a cylindrical structure, the edges of the sections overlapping, circumferential members surrounding the sections at intervals and formed of assembled strips forming continuous layers circumferentially, certain of the layers being narrower than others, and adjacent layers overlapping along circumferential lines to form broken joints, and tension devices surrounding the circumferential members and comprising hoops of approximately the width of the assembled strips, and means for se- 65 curing the ends of the tension members.

In testimony whereof I affix my signature.
JOHN H. COMER.
